UNITED STATES PATENT OFFICE

PAUL H. GRANGER, OF LOS ANGELES, CALIFORNIA

MEANS FOR DRAINING LIQUID FROM WELL TUBING

Application filed January 30, 1930. Serial No. 424,469.

This invention relates to a well tubing bleeder or means for draining liquid from well tubing, and the main object of the invention is to provide means whereby the liquid contained in an oil string or well tubing through which the oil or other liquid is pumped can be drained back into the well when the string of tubing is to be raised out of the well.

10 In the operation of wells such as deep oil wells, there is a column of liquid generally of great height extending upwardly from the working barrel to the top of the oil string or well tubing. In case it is necessary 15 to withdraw the oil string from the well for any reason, this body of liquid is raised with the tubing, it being understood that under these conditions the standing valve at the bottom of the working barrel remains 20 closed so that the oil is prevented from running out. In such withdrawal of the oil string from the well, it is customary to uncouple the tubing in stands of certain length and as each stand is uncoupled from the 25 string, the oil contained in such stand runs out from the stand, flowing and spattering over the operating platform and surrounding parts, causing great inconvenience and considerable danger to the operators on account of the slippery nature of the oil.

30 My invention provides for bleeding or draining off the oil or liquid from the oil string or well tubing before the same is elevated and removed from the well, thereby 35 doing away with the difficulty above referred to.

The accompanying drawings illustrate embodiments of my invention and referring thereto:

40 Fig. 1 is a vertical section of the tubing bleeder in normal or inoperative position.

Fig. 2 is a similar view showing the device in operated position.

45 Fig. 3 is an enlarged section of the catch means used to control the operation of the bleeder, the same being shown in position corresponding to that of Fig. 1.

50 Fig. 4 is a view similar to Fig. 3 showing the parts in position corresponding to that of Fig. 2.

Fig. 5 is a side elevation of the means shown in Fig. 3.

Fig. 6 is a section on line 6—6 in Fig. 5.

Fig. 7 is a section on line 7—7 in Fig. 4.

The tubing bleeder constituting my invention is adapted and intended to be attached to the lower end of a working barrel, such as indicated at 1 in Figs. 1 and 2, said working barrel having the usual standing valve 2 at its lower end controlling the entry of liquid 60 thereto. Attached to the lower end of the working barrel 1, for example, by means of a coupling 3, is a perforated section 4 of tubing, through which the oil or liquid to be pumped passes from the well bore to the standing 65 valve.

My invention comprises a tubular body 6 which is secured to the lower end of the perforate section 4 aforesaid by means of a coupling 7 and has secured thereto by means of 70 a coupling 8 a length of tubing 9 which is adapted to extend nearly to the bottom of the well when the working barrel is in operating position. A valve operating means consisting of a rod 10 extends within the members 4, 75 6 and 9 and is provided at its lower end with a cross bar or other means 11 for engaging with the bottom of the well as hereinafter described and is adapted to engage the movable member or ball of the standing valve 2 to 80 raise the same off its seat under certain conditions as hereinafter explained. Rod 10 may be provided with a cross pin 13 engaging in the slots 14 in the tubing 9 to guide and limit the motion of said rod and catch or 85 clutch means are mounted on said rod and within the member 6 for coupling or connecting the said rod to said member 6 under certain conditions as hereinafter set forth so as to hold the valve lifting means in raised 90 position. The clutch means for connecting the rod 10 with the tube 6 may comprise a member 15 screwing into the member 6 and having a square opening 16 through which a squared portion 17 of the rod may slide, said 95 member 15 being secured thereon or formed therewith. Bearing means 18 extending upwardly on opposite sides of the rod portion 17 and formed respectively with horizontal slots 19 in which slide dogs or catch members 100

20, the inner ends of which are adapted to engage under certain conditions under shoulders 21 on the rod portions 17, said shoulders being, for example, constituted by the upper 5 edges of notches 22 formed on opposite sides of said rod portions 17.

A movable clutch member 24 is mounted to slide on the rod portion 17 by means of a squared opening 25 on said member 24 and 10 has secured thereto and formed thereon downwardly extending projections 27 provided with inclined faces 28 on the inside thereof adapted to engage the outer ends of the respective sliding dogs 20 to force the 15 same inwardly, the said outer ends of said sliding dogs being preferably inclined in correspondence with the inclination of the operating faces 28 so as to provide an effective bearing for engagement therewith. In order 20 to retain the dogs in position on the supporting member 18, each dog may be provided with a horizontal slot 30 through which passes a pin 31 on the supporting means 18 and said slot 30 may have a depression 32 at 25 its outer end for the purpose of retaining the dog in operated position when it has been operated inwardly. The movable clutch member 24 is normally held in elevated position relative to the clutch member 15 by 30 means of springs 35 interposed between said clutch members, said springs surrounding and being supported by bolts 36 which are secured to the member 15 and pass through 35 openings in the upper member 24. Nuts 37 on said bolts engage the upper clutch member 24 to limit the upward movement thereof.

The operation of the device is as follows: When the oil string and working barrel are lowered into the well with the parts above 40 described attached thereto, and when the means 11 at the bottom of the rod 10 reaches the bottom of the well it arrests the further down movement of said rod and further lowering of the oil string and working barrel will 45 cause the standing valve to be opened by operation of said rod. It will, therefore, be understood that the oil string and the parts supported thereby will normally be raised somewhat so that the parts are allowed to 50 assume the position shown in Fig. 1, and the standing valve is therefore closed. The oil string can be raised or lowered as often as desired without operating the clutch means above described, provided that the level of 55 the liquid in the oil string is not higher than the level of the liquid within the well outside the oil string, this being the normal condition before the pump is set in operation. When the working barrel has been put into 60 operation and the oil string or string of tubing has been filled with oil or liquid in the normal pumping operation and it is desired to remove the oil string or string of tubing from the well, the said string is first 65 lowered so as to bring the means 11 in con-

tact with the bottom of the well and in the ensuing downward movement of the string of tubing to cause the parts to move to the position shown in Figs. 2 and 4.

In movement to such elevated position the 70 rod 10 raises the movable member or ball of the standing valve as shown in Fig. 2, thereby opening the standing valve and allowing the liquid in the oil string or string of tubing to flow down rapidly past the standing valve 75 and out through the perforated section 4. This rapid downward flow of the liquid and the deflection thereof outwardly from the tubing causes downward pressure of the 80 operating member 24 of the clutch means, causing said upper clutch member to move downwardly against the resistance of the springs 35 and bringing the inclined faces 28 in engagement with the outer ends of the 85 dog or catch means 20 so as to force the latter inwardly to position shown in Fig. 4 so that their inner ends engage onto the shoulders 21 on the rod portions 17 and hold the rod portions 17 and rod 10 in position to 90 retain the standing valve in open position. The oil string may then be withdrawn from the well being elevated and uncoupled a stand at a time without any efflux of oil or liquid from the respective stands as they are being uncoupled or removed. 95

In order to keep the clutching device above described clear of sand or dirt, it is preferred to provide the clutch operating members 15 and 24 with perforations 38 through which a portion of the fluid may pass at high velocity so as to sweep any sand or other solid material away from such parts. 100

I claim:

1. In combination with a well tubing string and a working barrel at the lower end thereof, said working barrel being provided with a standing valve, tubular means attached to the lower end of the working barrel, a valve operating member movably mounted within said tubular means and provided at its lower end with means for engaging in the bottom of the well to elevate said means relative to the standing valve, said valve operating means being adapted to engage the movable member of the standing valve when so elevated so as to open the standing valve, catch means for holding said valve operating member in raised position and a member movably mounted below the standing valve and adapted to be operated by outflow of liquid from the standing valve and adapted to operate said catch means to position for holding the valve operating member in raised position to retain the standing valve in open position. 105 110 115 120 125

2. A draining means for a string of well tubing comprising a tubular member adapted for attachment to the working barrel at the lower end of such string of well tubing, a valve operating member vertically movable 130

in said tubular means and provided at its lower end with means for engaging the bottom of the well to elevate said valve operating means relative to the tubular member,
5 said valve operating means being adapted to engage and lift the movable member of the standing valve of the working barrel and so elevate it, a clutch member mounted within said tubular member and provided with dogs
10 adapted to engage the aforesaid shoulder on said valve operating member, and a clutch operating member mounted to slide vertically within said tubular member and adapted to operate said dog to move same into engagement
15 to said shoulders, said clutch operating means being adapted to be operated by the down flow of liquid past the standing valve when said standing valve is open, such down-flow of liquid being due to difference in level
20 of the liquid within and outside of the tubing.
3. In combination with well tubing and standing valve means at the lower end thereof, valve operating means movably mounted on the tubing and adapted to engage the
25 bottom of the well so as to cause the valve operating means to move upwardly with respect to the well tubing when the tubing is lowered from normal position, said valve operating means being adapted to lift and
30 open the standing valve when so moved upwardly with respect to the well tubing and means responsive to flow of liquid from the tubing, when the standing valve is opened, to engage the valve operating means so as to
35 hold the standing valve in open position.

In testimony whereof I have hereunto subscribed my name this 17th day of January, 1930.
